Maurice Bloch
ATTORNEY

UNITED STATES PATENT OFFICE.

FERDINAND STRAUSS, OF NEW YORK, N. Y.

REMOVABLE HARMONICA MOUTHPIECE FOR WIND INSTRUMENTS.

Application filed February 4, 1928. Serial No. 251,819.

This invention relates to improvements in toy musical wind instruments and more especially to the mouthpiece thereof.

One of the objects of the invention is to provide an instrument of the character referred to, with a removable harmonica mouthpiece adapted to fit into various shapes and kinds of horns.

Another object of the invention is to provide a mouthpiece casing adapted to enclose a harmonica supported therein, so as to prevent any air blown therein from escaping through any crevice in the said casing, and thus make the harmonica give forth fuller and richer tones.

A further object of the invention is to provide a harmonica mouthpiece adapted to be removably held in a tone arm and comprising a harmonica and a two-part or sectional sheet metal casing therefor, one of the casing sections having a flange on each side thereof airtightly supported in turned-over extensions or flanges on the sides of the other casing section.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts throughout the several views, and then finally pointed out and specifically defined and indicated in the appended claim.

The disclosure made the basis of exemplifying the present inventive concept suggests a practical embodiment thereof, but the invention is not to be restricted to the exact details of the disclosure, and the latter, therefore, is to be understood from an illustrative, rather than a restrictive standpoint.

The inventive idea involved is capable of

receiving a variety of mechanical expressions, one of which, for the purposes of illustration, is shown in the accompanying drawings, in which.

Figure 1 is a side view of a wind instrument having my improved mouthpiece inserted therein,

Fig. 2 is a top plan view of the mouthpiece,

Fig. 3 is an end view thereof looking from the right of Fig. 2, and

Fig. 4 is an enlarged sectional view taken on line 4—4, Fig. 2.

Referring to the drawings in detail, 5 indicates a toy musical wind instrument comprising a tube 6, a saxophone shaped outlet 7, an elbow 8 and a mouthpiece 9. The 65 mouthpiece 9 comprises an upper casing section 10 and a lower section 11. Each of the casing sections is provided with a beaded portion 12, a semi-tubular portion 13 and a harmonica supporting end 14. The lower 70 section 11 is provided with an outwardly extending flange 15 on each side thereof, and the upper section 10 has a flange portion 16 on each side thereof which is bent over and around the flanges 15 of the lower section 11. 75

In assembling the mouthpiece, a harmonica 17 is placed between the supporting ends 14, the flanges 16 are bent around the flanges 15 and the flanges 16 are then pressed 80 down tightly around the flanges 15 so as to make them airtight or as nearly so as possible, to prevent any air blown into the mouthpiece while playing from escaping at the sides, and thus insure full, rich and melodious tones to emanate from the instrument.

The tubular portion 13—13 of the mouthpiece, is frictionally maintained in the elbow 8 and may readily be removed therefrom to be inserted into a different type of horn or instrument.

From the foregoing it will readily be seen that I have provided a harmonica mouthpiece for toy musical wind instruments, 95 which mouthpiece is adapted to be re-

movably maintained in a variety of different types of horns and which will be airtight at the sides thereof.

Having described my invention, what I claim as new and desire to secure by Letters Patent, is:

A mouthpiece for toy musical instruments, comprising a lower casing section, an upper casing section abutting the lower sec-

tion, a harmonica clampingly supported between the said sections, and a flange on each side of each of the sections, the flange on each side of one of the sections being bent over and around the flange on each side of the other section in a substantially airtight manner.

FERDINAND STRAUSS.
